UNITED STATES PATENT OFFICE.

JESSE C. HOWARD, OF COLUMBUS, OHIO.

PUMPING DEVICE.

1,358,153.

Specification of Letters Patent.

Patented Nov. 9, 1920.

Application filed November 6, 1915. Serial No. 59,919.

To all whom it may concern:

Be it known that I, JESSE C. HOWARD, a citizen of the United States, residing at Columbus, in the county of Franklin and State of Ohio, have invented certain new and useful Improvements in Pumping Devices, of which the following is a specification.

My invention relates to pumping devices and aims to provide a construction of pumping unit which may be utilized in a great many places, one very good example being in the rural districts where each individual house may be itself provided with a structure for giving running water wherever and whenever desired.

The essential object of my invention resides in the lubricating mechanism for maintaining certain of the pump parts in a thoroughly lubricated condition. This structure particularly takes the form of a hollow connecting rod structure and also a hollow bearing portion structure forming receptacles for the lubricant and a wick structure located within these receptacles to permit the proper flow of lubricant to the parts desired.

Figure 1 is a vertical longitudinal section taken through a pump unit in which my improved structure is incorporated and also showing the driving motor and its connections, and

Fig. 2 is a transverse vertical section taken through my pumping unit and showing a housing within which any preferred type of switch structure may be confined for controlling the operation of the motor shown in Fig. 1.

In these drawings, the entire mechanism is shown as being mounted upon a supporting base 1 which is provided with a pair of upstanding standards 2 and 3 for supporting the bearing members in which the pump operating shaft 18 is journaled. This base is also provided with an electric motor 4 having an armature shaft 12 carrying a worm 13 at its outer end by means of which the proper pumping motion is derived. This worm is designed to mesh with a worm wheel 14 held confined within a casing or housing structure 15 of which the removable cap 16 forms a portion. It will be noted by particular reference to Fig. 1 that the side of the casing 15 opposite from that to which the cap 16 is applied is provided with an outwardly extending bearing portion 17 for rotatably receiving the shaft 18 upon which

the worm wheel 14 is rigidly mounted. This bearing portion 17 is of a hollow nature and extends downwardly as is shown, the hollow portion 19 being so arranged that a receptacle is formed which is designed to be filled with lubricating oil and this oil is in turn communicated to the rotatable shaft 18 by means of the wick 20 which is held in contacting position with the shaft 18 by means of the coiled spring 21. The extreme outer end of the bearing portion 17 is also provided with an annular groove 22 into which any excessive oil carried by the shaft 18 is permitted to drop and which will then ultimately pass into the receptacle 19 through the small passage 23. At this point, it may also be well to relate that I intend to pack the casing 15 with a suitable lubricating grease in order that the gears 13 and 14 may at all times be in a perfectly lubricated state.

The shaft 18 carries a plurality of eccentric portions 24 the numbers of these eccentrics corresponding with the number of cylinders used and in the present instance, these eccentric portions are shown as being formed integral with the shaft 18. As illustrated, one end of this shaft is journaled in the outstanding bearing 17, while its opposite end is journaled in a similarly formed bearing 25 carried by the upper end of a bearing support 26, this latter bearing support being formed similarly in all essential respects as the bearing support for the bearing portion 17.

In the present case, I have shown three cylinders, these cylinders being designated 27 and each cylinder being provided with an inlet valve 28 and an outlet valve 29. These valves are carried in valve chambers 30 and 31 respectively and are held in close engagement with their valve seats by coiled springs 32 held confined in caps 33. Each of the valves 28 and 29 is in communication with the respective cylinders by means of passages 34 and 35 and all of the valve casings on the inlet side as well as on the outlet side, are in communication with each other so that a single inlet pipe 36 and a single outlet pipe 37 may be used. This outlet pipe 37 leads to a tank or other place of storage for use, while the small pipe shown at 38 is in communication with the outlet chambers, but leads to an automatic switch located upon the base 52 and confined within the housing 51. This switch forms no part of

the present invention. A piston 39 is movable up and down within each cylinder and in order that the proper suction may be had, each of these cylinders is formed with an 5 enlarged portion 40 at its upper end. Within this enlarged portion I place a series of gaskets 41 and 42, the gasket 41 being held in position by means of the member shown at 43, while the gasket 42 and, in fact, the 10 gasket structure as a whole, is held in position by means of the bushing 44 having threaded engagement with the enlarged portion 40 of each of the cylinders, as shown. By tightening or loosening this bushing 44, 15 the gaskets may be squeezed into firmer or looser engagement with the corresponding pistons 39, as may be desired. Each of these pistons is also preferably formed hollow, as is shown, and the arrangement is such that 20 they are vertically disposed so that they may form oil receptacles. Each piston is also provided with a cross head 45 to serve as a means of pivotal connection with the piston rod 46, each of these piston rods being also 25 formed hollow from their point of pivotal connection to the eccentric structure and each being further provided with apertures 47 adjacent the point of pivotal connection, in order to permit the inflow of oil from the 30 oil receptacle formed by the hollow piston. These apertures are specifically provided in order that the eccentric structures may each be kept in a thoroughly lubricated state by means of the wick 48 with the aid of the 35 springs 49. Particular reference to Fig. 2 will show that the band 50 for encircling the eccentrics 24 is formed integral with the piston rods and there will, therefore, be a relative movement between these bands and 40 the eccentrics which it is desired to keep thoroughly lubricated by means of the wick structure just described.

From the pump structure described, it will

be apparent that rotation of the shaft 18 will cause a continuous reciprocation of the 45 pistons within their cylinders. This reciprocation will cause an inflow of water into the cylinder and also an outflow through the pipe 37. During the operation of the pump, the parts are maintained in a thoroughly 50 lubricated condition so long as sufficient oil remains in the oil receptacles. This oil is fed to the bearing parts by means of the wicks shown and these wicks are held in position by means of their respective springs. 55 This feature I deem particularly valuable.

What I claim, is:

1. In a pumping unit, a vertically disposed cylinder, a hollow piston movable in said cylinder, a hollow piston rod pivotally 60 connected with said piston and extending out through the top side of said cylinder, said piston rod having an aperture adjacent said pivotal connection, an eccentric for the opposite end of said piston rod, and a spring 65 pressure wick structure within said hollow piston to transfer oil from said pivotal connection to said eccentric.

2. In lubricating mechanism for pumping units, the combination with a vertically 70 disposed cylinder having a reciprocating piston mounted therein, of an eccentric carrying driven shaft, a hollow connecting rod co-operative with said shaft, a piston for effecting the reciprocation of the latter, a 75 wick positioned in a lubricant containing chamber formed in said rod, and resilient means for forcing said wick into engagement with the shaft eccentric.

In testimony whereof I affix my signature 80 in presence of two witnesses.

JESSE C. HOWARD.
